UNITED STATES PATENT OFFICE.

STEPHAN ZGLICZYNISKI, OF BALTIMORE, MARYLAND.

SECTIONAL BOAT.

1,127,842.

Specification of Letters Patent.

Patented Feb. 9, 1915.

Application filed June 4, 1914. Serial No. 843,111.

To all whom it may concern:

Be it known that I, STEPHAN ZGLICZYNISKI, a citizen of the United States, and resident of Baltimore, in the State of Maryland, 5 have invented certain new and useful Improvements in Sectional Boats, of which the following is a specification.

My invention has relation to improvements in sectional boats and the primary object of the invention is to provide a boat 10 with suitable mechanism for operating the same, in which oars can be dispensed with and said mechanism be substituted therefor or both may be employed.

15 A further object is to provide a boat in sections so that if desired it may be folded together for transportation and to occupy but very little room in transit from place to place.

20 With these and other objects in view the invention consists in the novel construction and combination of parts as will be herein-after more fully and in detail described and the asserted novelty specifically claimed.

25 I have fully and clearly illustrated my invention in the accompanying drawings in which—

Figure 1 is a longitudinal section of the boat; Fig. 2 is an isometrical view. Fig. 30 3 is a view showing the sections of the boat 30 connected together for use.

Similar letters of reference indicate similar parts throughout the figures.

Referring to the drawings:—A designates 35 a boat which is made in sections preferably of steel, but if desired, may be of any other suitable material adapted for the purpose.

B designates a tubular section, and B' 40 designates a channeled section and interposed between said sections is provided a suitable rubber packing C, these elements being secured together by means of clamps D and screws E having their angular ends 45 perforated to admit the adjusting screws E being passed therethrough, for adjusting the elements or parts together.

F, designates a rod, the upper portion being provided with a hand-wheel E', and the lower portion with a pulley F', the lower end of the rod being pivotally fixed to the 50 bottom of the boat. To the pulley F' is secured one end of a string G, the opposite end of the string being secured to the upper end of a rudder stem G' by which the boat is steered in various directions as occasion 55 requires.

H, designates a sprocket wheel over which is passed a sprocket chain I, this sprocket wheel being journaled in the same manner as is usually done in bicycles. 60

J, designates a beveled gear wheel which is journaled in the same manner as the wheel H and has in mesh therewith a pinion J' and engages with the sprocket chain which revolves a propeller J² through the medium 65 of a shaft J³.

The usual seats are provided in the boat as well as the usual row locks when the boat is propelled by oars.

From the foregoing description taken in 70 connection with the accompanying drawings the operation of my boat will be obvious.

What I claim as new and desire to secure by Letters Patent is:

A sectional boat having fastening means 75 between adjacent sections, each comprising a tubular section, a channeled section located parallel therewith a rubber packing interposed between the two sections, clamps constructed as shown and described, adjusting 80 screws passed through the angular ends of said clamps, the free ends of which abut against the rear side of the channeled section, whereby through the medium of said screws the sections are firmly and securely 85 held together, substantially as and for the purpose set forth.

STEPHAN ZGLICZYNISKI.
